UNITED STATES PATENT OFFICE.

THOMAS H. SHEETS, OF SHINGLE, CALIFORNIA.

RAILROAD-TIE JACK.

Application filed July 19, 1927. Serial No. 206,984.

This invention relates to certain new and useful improvements in railroad tie jacks and has for its primary object to provide a jack for placing a tie in position beneath railroad rails and also for removing a worn tie.

A further object of the invention is to provide a railroad tie jack comprising a minimum number of parts capable of quick and easy assembly for the removal and placement of railroad ties beneath rails.

With the above and other objects in view that will become apparent as the nature of the invention is better understood, the same consists in the novel form, combination and arrangement of parts hereinafter more fully described, shown in the accompanying drawings and claimed.

In the accompanying drawings wherein like reference characters indicate corresponding parts throughout the several views,

Figure 1 is a fragmentary top plan view showing a rail tie, a rail and the tie jack operatively positioned with respect to the tie and rail;

Figure 2 is a fragmentary side elevational view showing the tie jack in its operative position;

Figure 3 is a cross-sectional view taken on line 3—3 of Figure 2 showing the supports for the side rack bars of the tie jack;

Figure 4 is a detail sectional view taken on line 4—4 of Figure 1;

Figure 5 is a fragmentary perspective view of one of the side rack bars; and

Figure 6 is a perspective view of the end bar connecting the side rack bars.

Referring more in detail to the accompanying drawings, wherein is illustrated the preferred embodiment of this invention, the reference numeral 1 designates a rail tie with a rail 2 supported thereon. The tie jack disclosed in this application is intended for the removal of a worn out tie and also for placing a new tie in position beneath the rail.

The tie jack comprises a frame having side hangers 3 connected by a brace rod 4 and each hanger carrying a strap 5 at its upper end, the straps 5 being connected by a bar 6 that is adapted to be positioned in contact with the width of the rail 2. The bar 6 at each end thereof carries a strap clamp 7 that engages the base flange of the rail 2 as clearly shown in Figure 2.

A rack bar 8 of the type shown in detail

in Figure 5 is positioned at each side of the tie 1, the rack bars 8 being supported in the grooved bracket or supporting arms 9 laterally projecting from the hangers 3. Corresponding ends of the rack bars 8 are formed with notches 10 at the upper and lower sides thereof and the connecting end bar 11 shown in detail in Figure 6 is associated therewith, the end bar 11 being notched at its ends as 60 at 12 to provide spaced lugs 13 that are received in the notches 10 of the rack bars. When the rack bars and end connecting bar are assembled and associated with the tie as shown in Figures 1 and 2, the end connecting 65 bar 11 is engaged with the adjacent end of the tie 1 for moving the tie transversely of the rail upon longitudinal sliding movement of the rack bars.

The shaft 14 is journaled at its ends in the 70 upper ends of the hangers 3 and the ends of said shafts within and adjacent said hangers carry forked arms 15 in which a pawl 16 is pivotally supported at 17, the pawls 16 gravitationally falling upon the upper toothed 75 side of the rack bars 8. The shaft 14 carries a stub handle 18 intermediate its ends and with which a relatively long handle 19 is detachably connected as shown in Figure 2. From the above detailed description of 80 the device, it is believed that the construction and operation thereof will at once be apparent, it being noted that the frame structure of the jack is positioned in engagement with the rail 2 while the rack bars 8 85 at each side of the tie 1 are connected at one end by the end connecting bar 11 which is positioned for engagement with the adjacent end of the tie 1. By moving the handle 19 to the left from the position shown in Figure 2, the pawl 16 ratchets over the rack bars 8 and when the handle 19 is moved in the opposite direction, the reverse rotation of the shaft 14 imparts movement to the pawls 16 and sliding movement of the rack bars 8, the end connecting bar 11 that is engaged with the end of the tie moving the tie from beneath the rail 2. The tie is removed in a step by step movement and in a similar manner a new tie is placed into position. In removing an old tie, the jack is placed in engagement with the outer side of the outer rail and the jack is placed in engagement with the inner side of the inner rail when a new tie is being placed into position.

While there is herein shown and described

the preferred embodiment of the present invention, it is nevertheless to be understood that minor changes may be made therein without departing from the spirit and scope 5 of the invention as claimed.

What I claim as new is:—

1. In a railroad tie jack, a pair of rack bars, and an end connecting bar placed in inclosing relations with respect to a tie, a 10 frame fashioned for engagement with the base flange and web of a rail at opposite sides of the tie, a shaft journalled in the frame, pawls carried by the shaft engaged with the rack bars, and a handle on the 15 shaft to effect oscillation thereof to cause the pawls to move the rack bars in a step-by-step movement.
2. In a railroad tie jack, a pair of rack bars, and an end connecting bar placed in 20 inclosing relations with respect to a tie, a

frame engaged with a rail, a shaft journalled in the frame, pawls carried by the shaft engaged with the rack bars, and a handle on the shaft to effect oscillation thereof to cause the pawls to move the rack 25 bars in a step-by-step movement, the frame including a pair of hangers and supporting arms on the hangers for the rack bars.

3. In a railroad tie jack, a pair of rack bars, and an end connecting bar placed in 30 inclosing relations with respect to a tie, a rail engaging frame, a shaft journalled in the frame, forked arms extending from the shaft, pawls carried by the forked arms engaged with the rack bars and operating 35 means for the shaft, the frame including a pair of hangers and supporting arms on the hangers for the rack bars.

In testimony whereof I affix my signature.

THOMAS H. SHEETS.
